UNITED STATES PATENT OFFICE

JAMES S. REID, OF CLEVELAND, OHIO, ASSIGNOR, BY MESNE ASSIGNMENTS, TO THE EATON AXLE & SPRING COMPANY, OF CLEVELAND, OHIO, A CORPORATION OF OHIO

CLOSURE

Application filed May 25, 1928. Serial No. 280,542.

This invention relates to improvements in closures and has particular relation to closures which for one reason or another are larger in diameter than the openings which they are adapted to close. More particularly, the invention relates to closures of this type which are adapted for releasable connection to the objects having the openings to be closed by rotary movement of said closures.

10 The general object of the present invention is the provision of an improved closure which is adapted to close an opening of less diameter than said closure, the closure being provided with simple yet effective means for 15 centering the closure relative to said opening so as to enable said closure to be readily positioned for the locking operation.

A more specific object of the present invention is the provision of a closure of the 20 type described which is neat and pleasing in appearance, strong or sturdy in character, and economical to manufacture.

Further objects of the invention are in part 25 obvious and in part will appear more in detail hereinafter.

In the drawing, which represents one suitable embodiment of the invention, Fig. 1 is a side elevation of a closure applied to the tubular filler neck of a tank or receptacle; Fig. 2 is a central vertical sectional view thereof, the section through the closure being on the line 2—2, Fig. 3; Fig. 3 is a bottom plan view of the closure; Fig. 4 is a top plan view of the filler neck; and Fig. 5 is a central vertical sectional view of said neck on the line 5—5, Fig. 4.

As here illustrated, the opening to be closed is the opening 1 in the tubular filler neck 2 of a receptacle 3, said neck being an integral 40 part of said receptacle or separate therefrom and suitably secured thereto, the present neck being provided with an annular base flange 4 for securing purposes. Said neck is provided at its upper end with an inwardly extending flange 5 terminating in a depending flange 6. At three circumferentially spaced points, parts of flanges 5 and 6 are cut away to provide passage-ways 7 for the locking fingers of the closure, as will later appear.

50 The cutting away of said flange parts pro-

vides three depending flange portions 6, and the lower edge of each of said flange portions is inclined to provide a cam surface 8 with which the closure locking fingers cooperate in effecting a detachable connection of the 55 closure to the filler neck. Preferably and as shown, each cam surface is provided at its rear end with a dwell or seat 9 to receive a closure finger when the closure is in fully locked position on the filler neck, and each 60 flange portion 6 is provided adjacent its dwell with a depending projection 10 to limit rotary movement of the closure, as will be readily understood.

The closure here illustrated for closing the 65 filler neck opening 1 comprises an outer wall and an inner wall separated to provide an air chamber 15 therebetween. The single member forming the outer wall includes a dome-shaped portion 16 and a depending 70 marginal skirt portion 17. The single member forming the inner wall includes a central dome-shaped portion 18, an intermediate portion 19 and a depending marginal skirt portion 20 non-rotatably secured to the skirt 75 portion 17 of the outer wall member, such as by a crimping operation.

The closure inner wall member is provided with three fingers for detachable locking engagement with the cam surfaces 8 of the filler 80 neck, and in the present embodiment of the invention, resilient fingers 22 are formed by shearing the intermediate portion 19 of the inner wall member. Said fingers extend downwardly and outwardly from the base of 85 the dome-shaped portion 18 of said member and terminate in transversely curved end portions 23 which are adapted to yieldingly engage the cam surfaces 8 of the filler neck. Preferably and as shown, said fingers are 90 provided at their bases with suitable re-enforcing or bracing means, such as the webs 24.

The closure is applied to the filler neck by passing the free end portions 23 of the locking fingers down through the three passage-ways 7 of said neck and then imparting clockwise rotary movement to the closure so as to cause its locking finger portions 23 to ride up the cam surfaces 8 of the neck until 95 said finger portions strike the stop projections 100

10, at which time said finger portions rest upon the dwells 9 at the rear ends of said cam surfaces. To remove the closure, it is only necessary to impart counter-clockwise rotary movement thereto which will cause the closure finger portions 23 to leave the dwells 9 and ride down the cam surfaces 8 until they reach the passage-ways 7, at which time the closure can be readily lifted from the neck.

10 In order to enable the closure to be easily and quickly positioned in proper position relative to the filler neck for connection thereto, the closure is provided with suitable means for centering the same relative to said neck. 15 In the present embodiment of the invention, said centering means comprises three circumferentially arranged depending flanges 29 formed by shearing the metal of the intermediate portion 19 of the closure inner wall member. When the closure is applied to the filler neck, said depending flanges enter the opening 1 of the filler neck and engage the inner surfaces of the depending flange portions 6 thereof, thereby centering the closure relative to the filler neck and enabling detachable locking connection therebetween to be easily and quickly effected.

If desired, an annular gasket of cork or other yielding material may be interposed 20 between the top flange 5 of the filler neck and the intermediate portion 19 of the closure inner wall member, thereby more effectively sealing the filler neck opening. Said gasket would surround the three centering flanges 29 and therefore cover the three slots 32 formed in the inner wall portion 19 by the shearing operation, such position of a gasket being indicated by the dotted line 33 in Fig. 3. However, when the closure is connected 25 to the filler neck, the closure air chamber 15 is vented to the inside of the filler neck and hence to the inside of the container 3 by the openings 34 in the closure inner wall formed as a result of the shearing operation to provide the closure locking fingers. To vent the closure air chamber to the outside atmosphere, one or more openings 36 may be provided in the dome-shaped portion 16 of the closure outer wall member, as will be readily understood.

What I claim is:

1. A closure for openings adjacent which are arranged opposed depending surfaces and opposed cam surfaces, comprising a member adapted to cover said opening and provided with opposed locking fingers adapted for cooperative engagement with said cam surfaces to effect detachable locking connection therebetween, said member being also provided with opposed depending lugs sheared from said member and adapted for engagement with said depending surfaces to thereby effect proper positioning of the locking fingers relative to said cam surfaces for the locking operation.

2. A closure for openings adjacent which are arranged opposed depending surfaces and opposed cam surfaces comprising a member adapted to cover said opening and provided with opposed locking fingers adapted for cooperative engagement with said cam surfaces to effect detachable locking connection therebetween, said member being also provided with opposed depending lugs sheared from said member and adapted for engagement with said depending surfaces to thereby effect proper positioning of the locking fingers relative to said cam surfaces for the locking operation, and a gasket associated with said member, said gasket being arranged to cover the openings in said member from which said lugs have been sheared. 75

3. A closure for openings adjacent which are arranged opposed depending surfaces and opposed cam surfaces, comprising a member adapted to cover said opening and provided with opposed locking fingers sheared from said member and adapted for cooperative engagement with said cam surfaces to effect detachable locking connection therebetween, said member being also provided with opposed depending lugs sheared from said member and adapted for engagement with said depending surfaces to thereby effect proper positioning of the locking fingers relative to said cam surfaces for the locking operation each of said fingers being arranged to extend between a pair of said lugs. 80

4. A closure for openings adjacent which are arranged opposed depending surfaces and opposed cam surfaces, comprising a member adapted to cover said opening and provided with opposed locking fingers adapted for cooperative engagement with said cam surfaces to effect detachable locking connection therebetween, said member being also provided with opposed depending flanges adapted for engagement with said depending surfaces to thereby effect proper positioning of the locking fingers relative to said cam surfaces for the locking operation, said fingers and said flanges being integral with said member. 85

5. A closure for openings adjacent which are arranged opposed depending surfaces and opposed cam surfaces, comprising a member adapted to cover said opening and provided with opposed locking fingers adapted for cooperative engagement with said cam surfaces to effect detachable locking connection therebetween, said member being also provided with opposed depending flanges adapted for engagement with said depending surfaces to thereby effect proper positioning of the locking fingers relative to said cam surfaces for the locking operation, said member being sheared to provide said fingers and said flanges. 90

6. A closure for openings adjacent which are arranged opposed depending surfaces 95

and opposed cam surfaces, comprising a member adapted to cover said opening and provided with opposed locking fingers adapted for cooperative engagement with said cam surfaces to effect detachable locking connection therebetween, said member being also provided with opposed depending flanges adapted for engagement with said depending surfaces to thereby effect proper positioning of the locking fingers relative to said cam surfaces for the locking operation, said member being sheared to provide a plurality of said fingers and said flanges arranged in alternate relation.

In testimony whereof I hereby affix my signature.

JAMES S. REID.
